UNITED STATES PATENT OFFICE.

MICHAEL ANGELO HIRSCH, OF FRANKLIN, PENNSYLVANIA.

CLIP OR ELASTIC-BAND ATTACHMENT FOR BOOKS.

No. 877,771.

Specification of Letters Patent.

Patented Jan. 28, 1908.

Application filed March 6, 1905. Serial No. 248,624.

To all whom it may concern:

Be it known that I, MICHAEL ANGELO HIRSCH, citizen of the United States, residing at Franklin, in the county of Venango and 5 State of Pennsylvania, have invented certain new and useful Improvements in Clips or Elastic-Band Attachments for Books, of which the following is a specification, reference being had therein to the accompanying 10 drawing.

My invention relates to the combination with books—particularly such as small memorandum books, bank pass-books, account books and the like—, boxes—particularly 15 such as small pasteboard boxes—, and other inclosures—particularly such as envelops, of a device or clip applied to such articles and adapted to attach thereto an elastic band, cord, tape, or the like, or to perform 20 other useful function, such as securing the flap of an envelop.

The invention may be more readily understood and explained by reference to the accompanying drawing illustrating several 25 embodiments thereof differing in minor details.

Figure 1 is an edge view of a bank pass-book having an elastic band attached thereto by a device or clip of my invention; Fig. 2 is a side elevation of the same partly in section; Figs. 3 and 4 are views similar to Figs. 1 and 2, of a slightly modified form of device or clip; Figs. 5 and 6 illustrate the operation of applying the clip to a book; 35 Fig. 7 is a view similar to Fig. 4 showing another slightly modified form of clip; Figs. 8, 9, 10 and 11 show still other modified forms of the clip.

Referring to Figs. 1 and 2, the metallic 40 clip (preferably made of well-known quality of wire suitably resilient for such purposes and bent to approximately the shape shown) comprises a retaining or anchoring stem 4, having at one end thereof a hook 3 which 45 at its bend extends through an opening in the book. At its extremity 2 the hook bears against or toward the outer surface of the book and is curled or bent back upon itself to avoid a sharp or rough point. Between 50 its said extremity and the point where its bend leaves the opening through the book, the book bows or arches outward away from the surface of the book, thereby forming what may be designated an eye 1. Nor-

mally, that is, before its application to the book, the distance between the extremity of the book and the stem 4 which it overhangs, is preferably less than the thickness of the material or wall of the article to which the clip is applied; it follows that the resilient tongue, formed by that part of the hook which is positioned at the outer surface of the book, bears at its extremity firmly against said surface. An elastic band 20, cord or the like, may be readily passed 60 into and out of the eye 2 by forcing it under the extremity of the hook, which yieldingly bears against the book.

The modified form of the device or clip shown in Figs. 3 and 4 differs from the clip 70 of Figs. 1 and 2 in having the extremity of its hook bent to form a loop 6 in a plane approximately parallel to the surface which it is to engage. The extremity of the hook thus has a more extended surface for bearing 75 against the surface of the book.

In the form of clip shown in Fig. 7, the extremity 7 of the hook is bent downward and upward in a reverse direction to the bend at the extremity of the hook of Fig. 2. 80

The device or clip of Figs. 5 and 6 is similar to that of Figs. 1 and 2, except that the extremity of the hook is not bent back upon itself. These views illustrate the preferred manner of applying the clip to a bank 85 pass-book. The book is opened at its middle and a hole punched through it at what may be designated its hinge-line or line of fold. With the book partly open, as shown in Fig. 5, the stem 4 of the clip is 90 forced through the punched hole, until the bend of the book is finally brought to position through said hole, as shown in Fig. 6. The clip is then turned to cause the stem 4 to extend along and make contact with the 95 inner surface of the book at the line of fold, as shown in Figs. 1 to 4. With the book closed, holding the retaining or anchoring stem 4 between opposing inner surfaces of the book, it will be impossible for the clip 100 to become turned to one side or the other from its position shown in Figs. 1 and 2. Should the clip become slightly turned upon opening the book, the subsequent closing thereof will return the clip to its proper 105 position. The clip may, of course, be applied in other positions than at the line of fold of a book or article.

Fig. 11 shows the clip of Figs. 4 and 5 of slightly different dimensions for use with a book or article having a thinner wall.

In the modified form of clip shown in Fig. 8, the end 8' of the retaining or anchoring stem extends upward through and is bent down against the outer surface of the wall of the article to which the device is applied, the extremity of the hook 8 overhanging 10 said end of the stem.

In Fig. 9 the retaining or anchoring stem is formed with a pronged, sharpened or pointed end 9' entering the inner surface of the wall of the article to which the clip 15 is applied.

The clip of Fig. 10 resembles that of Fig. 8, the hook 10 and stem 10' differing in obvious respects from corresponding parts of Fig. 8.

20 The elastic band, cord or the like, attached to an article in the manner explained, may serve various purposes, such, for example, as affording a means adapted to extend around the article to hold it closed (especially useful in the case of bank pass-books), or a means for suspending the article or attaching it to other articles.

What I claim is:—

1. The combination with an article such 30 as specified, of a metallic device or clip consisting of a retaining or anchoring stem having a hook at one end thereof, said hook forming an eye at the outer surface of the article and at its bend extending through an 35 opening in the article to the stem which engages an inner surface of the article.

2. The combination with a book, of a metallic device or clip consisting of a retaining or anchoring stem having a hook at one 40 end thereof, said hook forming an eye at the outer surface of the book and at its bend extending through an opening in the book at the line of fold thereof to the stem which

latter extends along and makes engagement with an inner surface of the book at approximately the line of fold thereof. 45

3. The combination with an article such as specified, of a metallic device or clip consisting of a retaining or anchoring stem pointed at one end and having a hook at its 50 other end, said hook forming an eye at the outer surface of the article and at its bend extending through an opening in the article to the stem which engages an inner surface of the article. 55

4. The combination with an article such as specified, of a metallic device or clip consisting of a retaining or anchoring stem having a hook at one end thereof, said hook forming an eye at the outer surface of the 60 article and at its bend extending through an opening in the article to the stem which engages an inner surface of the article, and an elastic band, cord or the like passing through said eye of the metallic device or 65 clip.

5. The combination with an article such as specified, of a metallic device or clip consisting of a retaining or anchoring stem having a hook at one end thereof, said hook extending through an opening in the article with said stem engaging an inner surface of the article, and a part of the hook at the outer surface of the article bowing or arching outward away from said surface between the 75 extremity of the hook—which latter bears against or towards said surface—and the part of the hook which passes into the opening in the article. 70

In testimony whereof I affix my signature 80 in presence of two witnesses.

MICHAEL ANGELO HIRSCH.
